UNITED STATES PATENT OFFICE.

HERMAN EDWARD STURCKE, OF BROOKLYN, NEW YORK.

SPRAYING OR ATOMIZING APPARATUS.

1,303,987.

Specification of Letters Patent. Patented May 20, 1919.

Application filed May 14, 1915. Serial No. 28,102.

To all whom it may concern:

Be it known that I, HERMAN EDWARD STURCKE, a citizen of the United States, and resident of Brooklyn, in the county of Kings and State of New York, have invented certain new and useful Improvements in Spraying or Atomizing Apparatus, of which the following is a specification.

10 This invention relates to improvements in spraying systems such as are employed for spraying liquid compositions including paint or the like, although it will be understood that the invention is generally applicable to the spraying of all classes of materials.

20 The object of my invention is to provide devices in a system of this character which will simplify the operation of painting or spraying and increase the efficiency of the apparatus in use.

Some preferred forms of the invention will now be described in reference to the accompanying drawings, in which;

25 Figure 1 is a part-diagrammatic, part-perspective view of a system in accordance with a preferred embodiment of the invention, in which there is provided means controllable by the operator in the painting position, for regulating the pressure in the paint receptacle.

30 Fig. 2 shows a system provided with means controllable in the painting position for regulating both the pressure in the paint receptacle and the pressure of the jet of gas issuing from the nozzle of the painting tool or brush.

Fig. 3 shows in perspective a simple spraying system embodying the invention.

40 Fig. 4 shows a painting brush provided with means for regulating the pressure in the paint receptacle.

45 Fig. 5 shows a preferred form of regulating or pressure reducing valve of well-known kind employed in connection with the invention.

Fig. 6 shows a painting system in which the paint is fed under gravity.

50 Fig. 7 shows a system employing a force pump for feeding the paint to the brush.

The operation of a brush for painting or spraying by a blast of pressure gas such as compressed air, carbon dioxid under pressure, or the like, presents a serious difficulty 55 when used for painting on a large scale, such as the exterior of buildings, bridges or

even ordinary interiors in that the pressure at which the paint is supplied at the nozzle of the brush varies within wide limits, thereby varying the velocity at the nozzle 60 to such an extent as to make it almost impossible to paint with nicety. In systems in which the paint is supplied under pressure by admitting gas under pressure to the top of the paint receptacle, thereby 65 forcing the paint out through the paint outlet into the flexible connection leading to the paint brush, the position of the paint brush naturally varies relative to the position of the paint receptacle, and 70 this variation in the distance between the paint receptacle and the paint brush in a vertical direction affects the pressure at which the paint is supplied in view of the fact that a given pressure at the paint receptacle will deliver the paint at a predetermined velocity at a given point, but the 75 velocity of the paint will increase or decrease proportionately according as the paint brush is raised or lowered from said 80 given point. This problem is one of particular difficulty in the case where the painter is painting surfaces which are inaccessible, such as exteriors, etc., where the painter stands upon a ladder or other small 85 platform which makes it practically impossible to carry a paint receptacle containing a large quantity of paint close at hand. When painting under such conditions, owing to the wide variations in the paint pressure, it is necessary for the painter as he moves up and down the ladder to make frequent trips to the paint receptacle to adjust 90 the pressure therein by means of the reducing valve with which such receptacles are 95 usually provided, and this frequent interruption of work not only limits the range over which the painter can apply the paint, but also renders the operation of painting in 100 this manner fatiguing and inefficient.

It will be obvious that the same difficulty exists when the paint is fed to the brush under gravity from a point located above it, and also in the less usual case when the paint is forced by means of a feed pump or 105 the like to the brush.

In accordance with my invention, I provide means for overcoming the aforementioned defects in apparatus of this character, thereby enabling the painter or user of 110 the apparatus to cover a wide range of surface within limits imposed only by the

length of the hose connections between the paint brush and the receptacle. Moreover, I avoid any necessity on the part of the operator to interrupt his work and move 5 from the position where he is painting to the position where the paint receptacle is located in order to regulate the pressure of said receptacle to correspond with variations in the vertical distance between it and 10 the paint brush. A further advantage of the invention resides in the fact that pressures at the paint brush varying only through a small range which does not interfere with efficient work, can be secured, 15 notwithstanding the fact that the paint receptacle is located some considerable distance either above or below the position where the painting is being carried on.

The preferred form of the invention illustrated in Fig. 1 will now be described.

Referring to said figure, 1 is a receptacle containing compressed air, carbon dioxid or like pressure medium, which passes from the outlet 2 of said receptacle into a pressure 25 reducing or regulating valve 3 of well-known kind, the construction of which is later described with reference to Fig. 5. Connected with the outlet 4 of said valve 3 is a flexible pipe or hose 5 connected with the T-connection 6 of a regulating valve 7 mounted upon a panel 8 and provided with body-securing means, here shown as a leather strap 9, and adapted to be secured in buckle 10, whereby 30 the panel can be carried by the painter, who will support same by passing the strap 9 over his shoulder. A pipe 11 leads from the other end of said T-connection 6 to the brush 12 of well-known form, said pipe 11 being also flexible and of suitable length to 35 permit of the free movement of the brush by the operator. The brush comprises a hollow inlet 13 also serving as a handle, at the upper end of which is a valve contained in the valve casing 14, which valve controls 40 the passage of the air or gas into the nozzle 15. The aforesaid valve is controlled by means of a lever 16, which is connected with the valve spindle 17 of valve 18, controlling 45 the passage of paint through the paint nozzle 19, the paint being fed into said nozzle 50 as hereinafter described through the flexible connection 20.

The air or gas under pressure entering 55 the regulator 7 carried by the panel 8 passes therethrough, and its pressure is suitably reduced by adjusting the handle 21 of said regulator until the desired pressure in the paint receptacle is obtained, this being indicated by any suitable well-known pressure-indicating means such as the gage 22. The 60 gas at the desired pressure from said regulator then passes through the flexible connection 23 to the inlet 24 of the paint receptacle 25, said inlet being controlled by the manually operated valve 26. A cock 27 con-

nected with the flexible connection 23 and mounted on panel 8 may be opened to connect the upper end of the paint receptacle to the atmosphere if it is desired to release the pressure from the paint and thereby 70 stop the feed thereof due to the pressure of the fluid remaining at the top of the receptacle after the pressure reducing valve 7 has been operated to cut off or to reduce the supply of pressure fluid to the paint receptacle. 75

The operation of my improved system is as follows:—Before commencing to paint, the operator regulates the pressure of the atomizing fluid which is to issue from the 80 nozzle 15. This is done by operating the handle of the pressure regulating valve 3, whereby the required degree of gas pressure will be obtained and owing to the lightness of these gases, the pressure of the gas at the 85 nozzle 15 will be substantially constant even though the nozzle be raised or lowered for a great distance relative to the gas container.

The operator then places the strap 9 over his shoulder, so that he himself supports the 90 panel 8, and he then adjusts the handle 21 of the regulating valve 7 to secure the desired gas pressure at the top of the paint receptacle. The actuation of the lever 16 by the painter will then admit gas to the 95 nozzle 15 and paint to the nozzle 19 by the opening of the valves 14 and 18. Assuming that the painter is working on the side of a wall and commences at the bottom and works upwardly, it will be apparent that when he 100 is painting the lower-most surface of the wall, he will require a relatively low pressure at the top of the paint receptacle in order to force a small column of the paint in the pipe 20 out of the nozzle 19 at the 105 required velocity. Having set the regulating valve 7 to admit the gas at the necessary pressure to the paint receptacle, the operator proceeds to paint the lower part of the wall and then continues with the 110 upper portions. Assuming that the paint receptacle is standing on the ground, it will be obvious that as the painting takes place at a point farther away from the paint receptacle in a vertical direction, the column 115 of paint to be lifted by the gas pressure will be higher, and consequently the position for which the regulating valve 7 is set is incorrect for painting at this time, since the pressure of the gas on top of the paint will 120 impart too slight a velocity to the stream of paint issuing from the nozzle 19. Owing to the fact that the means for regulating the feed of the paint supply is located in proximity to the paint brush itself, and is carried by the painter it will be apparent that in the embodiment of my invention here illustrated, all it is necessary for the operator 125 to do at this time, in order to obtain the same flow of paint as he used in painting the 130

lower portions, is to adjust the regulator 7 to such an extent that the velocity of the issuing paint is substantially the same throughout all the different positions at 5 which painting takes place. There is no need for the operator to make any trips to the paint receptacle, and the receptacle, which may be as large as desired, may be arranged either below or above him in the 10 most convenient position with similarly beneficial results.

The conditions are somewhat different when the painter starts at the top of the wall and paints downwardly. In order to force 15 the high column of the relatively heavy paint to the top of the wall, it is necessary to operate the regulator 7 to admit high pressure gas to the top of the paint receptacle 25. As the painter proceeds downwardly, the regulator will require progressive adjustment to reduce the pressure of the fluid supplied to the paint receptacle, otherwise this pressure would be too great and the paint would be delivered at too high 20 a velocity. It would not be sufficient, however, to rely upon the regulator 7 alone for the reduction of pressure, owing to the fact that the top of the paint receptacle is at this time filled with gas at the high pressure used 25 for painting the uppermost parts of the wall. It is therefore desirable, in order to reduce the pressure progressively when moving downwardly, not only to operate the regulator 7, but also to open the cock 27, 30 which vents the top of the paint receptacle, thereby reducing the pressure in the top of said receptacle, which, after the cock 27 has been closed, will contain gas at the pressure determined by the regulator 7.

40 Fig. 2 illustrates a modified form of my invention in which provision is made whereby the operator may regulate the pressure of the stream of gas issuing from the nozzle without having to leave the painting position, and without affecting the adjustments 45 of the regulating means of the pressure paint feed. Referring to said figure, the apparatus is substantially the same as that shown in Fig. 1, except for the fact that 50 there is interposed between the paint brush 14 and the pipe 11, a manually adjustable regulator 28 and gage 29, whereby the pressure of the gas issuing from the nozzle 15 may be varied without any adjustment of 55 the regulator 3 located on the source of supply 1. This arrangement is especially useful for cases where the painting takes place at such a high elevation that the pressure required to be supplied to the paint receptacle 60 from the gas receptacle 1 would be so high that the same pressure at the nozzle 15 would not be desirable. By means of the arrangement described in Fig. 2, it would be possible to supply air or gas under pressures varying 65 through a wide range to the paint re-

ceptacle, without producing an atomizing blast of too great a velocity, and all this can be done by the operator without having to leave the painting position.

After the painting has ceased in the construction shown either in Fig. 1 or Fig. 2, the pressure gas tending to pass into the paint receptacle is shut off by adjustment of the regulator 7. Notwithstanding the fact that this valve is closed, there will still 75 be a certain amount of pressure gas contained in the paint receptacle 25, and the flexible connection 23 leading thereto. This gas is admitted to atmosphere by opening 80 the cock 27.

It will therefore be noted that this cock 27 is preferably opened whenever it is desired to secure a reduction in the pressure at the top of the paint pot, whether or not this reduction is required owing to the fact 85 that the painter is descending from a high painting position to a low painting position as described above, or owing to the fact that he has actually finished painting and wishes to avoid the possibility of any undesired 90 ejection of paint from the paint receptacle, due to unauthorized or accidental operation of the painting tool or as the result of any other accident. It will moreover be apparent that owing to the reduction of pressure 95 in the paint receptacle, the paint contained in the flexible connection 20 can run back into the paint receptacle after use. It will be understood that the flexible connection or hose pipe leading from the regulator 7 100 to the paint receptacle can be of very narrow bore in view of the fact that the pressure in the paint receptacle is static. The regulator 7 and associated connections are secured to the panel 8 by bridges 30, screwed 105 or otherwise suitably connected with the panel, and the entire portable regulating device is made of light material, so as not to constitute too heavy a burden to the painter. At the same time, owing to its compactness, 110 the device does not impede the painter in his movements, even when the painting is carried on in extremely dangerous places. Indeed, the greatest danger in carrying on 115 painting under such conditions is that the operator must, with the old type of air-brush system, constantly make trips from his position to the paint receptacle, and it is while making such changes in position that accidents are liable to occur. Where a liquid 120 or compressed gas such as carbon dioxide is employed as the motive medium, I prefer to use same in conjunction with the means described in the U. S. application Serial No. 22,371, filed April 19, 1915, Levy (Case 5), 125 and the apparatus described in my co-pending application Serial No. 28,101, filed May 14, 1915. While I have here shown a receptacle for a compressed gas or liquid gas as 130 the source of supply of the motive medium,

it will, of course, be understood that said source may be an air compressor, or any other suitable means for supplying pressure gas. In the embodiment of my invention shown in Fig. 3, with reference to a spraying device, it will be seen that the painter carries in his hand a spraying nozzle 31, connected by hose 32 with the paint receptacle 33. The paint is fed under pressure to said nozzle by the compressed air supplied from the reservoir 34 filled by the pump 35 driven by a gasoline engine 36 and supplied through connection 37 to regulator 38 and connection 39 to inlet 40 of the paint receptacle. The cylindrical portions 41, 41 of the regulator are connected by collars 42, 42 by which said regulator is secured to the cross straps 45, 45 said cross straps being connected to shoulder straps 46, 46, whereby the regulating means can be conveniently carried by the painter without hampering him in his movements.

While it is more convenient to arrange so that the means for regulating the pressure at the top of the paint receptacle is carried upon the person of the painter himself, it is also possible, though not so satisfactory, to arrange these means upon the painting tool itself. Such a construction is illustrated in Fig. 4, in which the gas supply pipe 47 is connected with the hollow handle 48 of the painting tool, the bore of which is connected by a branch pipe 49 with the regulator 50, indicator 51 and cock 52, which parts are similar in all respects to the parts, 7, 22, 27 of Fig. 1. The thin pipe 53 leads to the top of the paint receptacle. Except for this modification, the painting tool is exactly the same as that illustrated in Figs. 1 and 2.

The pressure regulating or reducing valves herein referred may be of any suitable well-known kind capable of adjustment to vary the pressure of the fluid passing therethrough. One such valve 7, of well-known type, is illustrated in Fig. 5 and comprises a casing consisting of two members 54, 55, between which is suitably secured a diaphragm 56 upon which is mounted a seat-supporting member 57 provided with a seat 58 covering the small opening 59 at the conical end 60 of the pipe 61 leading from the T-piece 67, to which the pipe 5 is secured as described with reference to Fig. 1. Bearing on the other side of said diaphragm is a spring 62 the tension of which can be regulated by means of a nut 63, mounted on screw shaft 64 bearing in the casing and provided with the operating handle 61^a. The outlet 65 conducts the gas from the valve 7 to the indicator 22 of any suitable well-known form, and pipe 23 to the paint receptacle. It will be apparent that the extent of pressure reduction is dependent upon the tension of the spring, and this can be varied by adjustment of the operating handle 21.

In the construction illustrated in Fig. 6, I have shown a gravity-feed paint system, and in the example here illustrated, this system is shown in operation for the purpose of painting the side of a boat 68. The paint is contained in a receptacle 69, situated on the deck of the boat, and the paint passes through the flexible connection 70 to the painting tool 71. Supported on the painter by straps 72 is a panel 73 carrying a fluid regulating valve 74 of any suitable type adapted for reducing the pressure flow, such as is illustrated in Fig. 5, and it will be obvious that the operator can set this valve for a desired pressure which pressure will be maintained automatically by the valve, irrespective of the vertical distance between the painting tool 71 and the paint receptacle 69. It will, of course, be obvious that the painting regulator need not be carried upon the person of the painter, and I have shown herein a second painter provided with a painting tool 71^a, with regulator 74^a mounted thereon, instead of being mounted on a panel as is the case with the regulator 74. The painting tools 71, 71^a are controlled by handles 72^a.

In the construction shown in Fig. 7, the paint contained in the receptacle 75 mounted on the carriage 76 passes through the pipe 77 to force pump 78, driven by gasoline engine 79, and the paint passes from the outlet of said pump through the flexible connection 80 leading to painting tool 81. The throttle valve 82 of the engine 79 is held in wide open position by spring 83, and said valve is adapted to be operated against the action of said spring by means of the flexible Bowden transmission 84 terminating in handle 85 pivoted on lug 86 and provided with a spring detent 87 adapted to take into notches in the face of the segment 88. When the painter is painting the lower positions, he operates the lever 84 to actuate the throttle valve to reduce the supply of gas to the gasoline engine, thereby reducing the speed at which the pump is driven, and consequently reducing the pressure of the paint issuing from the nozzle of the painting tool. As the painter paints the higher portions of the vessel or the like, he actuates the lever 84 to release the throttle, which opens to a greater extent, thereby permitting the gasoline engine to exert greater power and causing the pump to force a stream of paint at the desired higher pressure to the painting tool. It will be obvious that instead of controlling the gasoline engine, the pump itself could be directly controlled by means located on the painting tool or in proximity therewith.

It will be understood that the various constructions shown herein are susceptible of wide variation and modification without departing from the spirit of the invention,

which broadly contemplates the provisions of means located in proximity with the spraying tool, operable to vary the pressure upon the paint in the receptacle, and the invention also contemplates the provision of automatic means located in proximity with the painting tool for maintaining a substantially constant flow of material therethrough.

10 It will be understood that by the term "gas" employed herein, I intend to include any suitable gas, such as carbon dioxide gas or air. By the term "body-securing means" in the claims, I intend to include any suitable means, such as straps, pockets or the like, for securing the regulating means to the human body, so that it can be supported by the body of the person who is using the painting or spraying tool.

20 It will be understood that my invention is particularly applicable to the case where the paint pot is stationary; that is to say, it is placed in a determined position during the painting operation, the operator moving 25 relative to the paint pot. In the claims which follow, I have referred to the paint pot as being stationary, in contradistinction to that class of apparatus in which the paint pot is actually carried upon the shoulders of 30 the operator, in which case the conditions which are avoided by the present invention do not exist.

It will, of course, be understood that my paint pot can be moved from place to place, 35 and that it is not ordinarily intended the same should be carried upon the shoulders of the operator.

What I claim is:

1. In a spraying apparatus of the kind 40 described, a stationary receptacle for the material to be sprayed, means for applying pressure to the contents of said receptacle, a spraying tool connected with said receptacle and located at a distance therefrom, and 45 means in proximity to the spraying tool for regulating the pressure applied to the contents of said receptacle to a desired degree and for automatically maintaining said degree of pressure applied to the receptacle.

50 2. In a spraying apparatus of the kind described, a stationary receptacle for the material to be sprayed, means for applying pressure to the contents of said receptacle, a spraying tool connected with said receptacle and located at a distance therefrom, and 55 portable means in proximity to the spraying tool for regulating the pressure applied to the contents of said receptacle to a desired degree and for automatically maintaining 60 said degree of pressure applied to the receptacle.

3. In a spraying apparatus of the kind 65 described, a receptacle for the material to be sprayed, means for applying pressure to the contents of said receptacle, a spraying tool

connected with said receptacle, and portable means adapted to be located at a distance from said receptacle and in proximity to the spraying tool for regulating the pressure applied to the contents of said receptacle to 70 a desired degree and for automatically maintaining said degree of pressure applied to the receptacle.

4. In a spraying apparatus of the kind described, a receptacle for the material to be 75 sprayed, means for applying pressure to the contents of said receptacle, a spraying tool connected with said receptacle, portable regulating means for controlling the pressure applied to the contents of said receptacle to a desired degree and for automatically maintaining 80 said degree of pressure applied to the receptacle, and a flexible connection between said portable regulating means and said receptacle. 85

5. In a spraying apparatus of the class described, a stationary receptacle for the material to be sprayed, means for regulating the pressure feed of the material to be sprayed, and body-securing means supporting 90 said regulating means in proximity to the spraying tool.

6. In a spraying apparatus of the class described, a stationary receptacle for the material to be sprayed, means for regulating 95 the pressure feed of the material to be sprayed, and body-securing straps associated with said regulating means in proximity to the spraying tool.

7. In a spraying apparatus of the kind described, in combination, a source of pressure gas supply, portable regulating means for regulating the pressure applied to the receptacle to a desired degree and for automatically maintaining 100 said degree of pressure applied to the receptacle, a spraying tool, a receptacle for the material to be sprayed, a flexible connection between said source of pressure gas supply and said spraying tool with means for admitting pressure gas into 105 one side of said portable regulating means, a flexible connection connected between the other side of said regulating means and the receptacle to admit pressure gas to said receptacle, and a flexible connection between 110 said receptacle and said spraying tool.

8. In an apparatus of the class described, a source of pressure gas supply, portable regulating means for regulating the pressure applied to the receptacle to a desired degree 115 and for automatically maintaining said degree of pressure applied to the receptacle, a spraying tool, a receptacle for the material to be sprayed, a flexible connection between the source of gas supply and said tool, a second regulating means interposed in said flexible connection and located in proximity to said tool, means for admitting pressure gas from said flexible connection to said portable regulating means, a flexible connec- 120 125 130

- tion between said regulating means and said receptacle adapted to conduct gas which has passed through said portable regulating means to said receptacle, and a flexible connection between said receptacle and said tool.
9. In a spraying apparatus of the class described, means including a source of fluid pressure supply, a receptacle, flexible connections between said source of supply and 10 said receptacle, portable regulating means associated with said flexible connections, and means in proximity to said portable regulating means for admitting air at atmospheric pressure to said receptacle.
- 15 10. In combination with a spraying apparatus of the class described, a pressure regulator, an indicator, a supporting means for said pressure regulator and indicator, and body-securing means connected with said 20 supporting means.
11. In combination with a spraying apparatus of the class described, a pressure-reducing valve, a cock connected to the outlet of said pressure-reducing valve, and body-se- 25 curing means connected with said members.
12. In a spraying apparatus of the kind described, a receptacle for the material to be sprayed, a spraying tool connected with said receptacle, and portable adjustable automatic means in proximity to the spraying tool and remote from said receptacle for 30 regulating the pressure of the material to be sprayed issuing through the spraying tool.
13. In a spraying apparatus of the kind 35 described, a stationary receptacle for the material to be sprayed, a spraying tool, means for regulating said tool, connecting means between said spraying tool and said receptacle, means for applying pressure to the 40 material to be sprayed to force it through said connecting means to the spraying tool, and means in proximity to the spraying tool for regulating the pressure applied to the material to be sprayed and operating inde- pendently of the means for regulating said tool.
14. In a spraying apparatus of the kind described, a spraying tool, means for regulating said tool, a stationary receptacle for the material to be sprayed, pressure feeding means, connecting means between said tool and said receptacle, and means on the tool for regulating said pressure feeding means and operating independently of the means for regulating said tool.
15. In a spraying apparatus of the kind described, a stationary receptacle for the material to be sprayed, means for applying pressure to the contents of said receptacle, a spraying tool connected to said receptacle and located at a distance therefrom, means for applying pressure to said tool for atomizing the material to be sprayed, and means in proximity to the spraying tool for regulating the pressure applied to the contents of said receptacle to a desired degree and for automatically maintaining said degree of pressure applied to the receptacle.
16. In a spraying apparatus of the kind described, a stationary receptacle for the material to be sprayed, means for applying pressure to the contents of said receptacle, a spraying tool connected to said receptacle and located at a distance therefrom, means for applying pressure to said tool for atomizing the material to be sprayed, and means in proximity to the spraying tool for regulating the pressure applied to the contents of said receptacle without changing the pressure applied to the tool.
- Signed at Brooklyn in the county of Kings and State of New York this 13th day of May A. D. 1915.
